(57) **CLAIM**

The ornamental design for a tumbler bottle, as shown and described.

DESCRIPTION

FIG. 1 is a perspective view of a tumbler bottle illustrating a configuration of my new design;
FIG. 2 is a front plan view thereof;
FIG. 3 is a rear plan view thereof;
FIG. 4 is a right side plan view thereof; and,
FIG. 5 is a left side plan view thereof.
The broken lines shown in the drawing are for illustrative purposes only and form no part of the claimed design.
